METHOD OF BENDING METAL STRIPS

William Schukraft, Chicago, Ill.

Application December 14, 1942, Serial No. 468,922

9 Claims. (Cl. 153—10)

The invention relates to a method of bending metal strips and more particularly to the bending of long, straight, thin and relatively wide strips into a form in which they are arcuate longitudinally substantially in the plane thereof.

The present invention has particular utility in the fashioning of metal strips used in airplane constructions. Referring particularly to the "de-icer" arrangements as used on certain airplane constructions, the sheet of rubber which is disposed over the leading edges of the wings and parts of the tail assembly are held in place marginally by strips of aluminum alloy metal. These strips are elongated and may vary in length; they are relatively wide and thin, and in transverse cross section are arcuate and of tapering thickness. Straight strips of this form can be and are formed by an extruding process. However, the de-icer assemblies require in addition to straight strips, some that are arcuate longitudinally substantially in their planes, to follow the radius on which the wing tips and edge surfaces on the tail assembly are formed. In other words, these arcuate strips must have an edgewise bend. Such strips cannot be extruded but are produced by a relatively slow and expensive cutting and shaping process. Such strips cannot simply be bent edgewise since they "buckle" or acquire a rippled effect along the inner edge of the strip. In the strips of tapering cross section described above this effect is especially pronounced because the thinner edge is the inner edge.

The general aim of the invention is to provide a novel method for forming such longitudinally arcuate strips rapidly and efficiently.

Another object is to provide a new and improved method of this character in which one or more straight strips to be bent are confined tightly against any movement transversely of their planes, as by being encased in a heavy metal enclosure, the entire unit then being bent to impart the desired curvature to the encased strips and transverse bending or buckling being substantially prevented by the heavy enclosure means.

In conjunction with the foregoing, an object is to provide in such a method the steps of bending the encased units first to a smaller radius than that desired and then reversing the bending to the desired radius whereby to further diminish the buckling effect.

Another object is to provide a novel method of forming such strips of arcuate cross section in opposed pairs.

Other objects and advantages will become ap-

parent in the following description and from the accompanying drawings in which:

Figure 1 is a perspective view of a straight metal strip prior to bending by the process embodying the features of the invention.

Fig. 2 is a side view of an encased unit after bending.

Fig. 3 is a perspective view of a bent strip after removal from the encasing means and showing 10 the buckling effect on an exaggerated scale.

Fig. 4 is an end view of an encased unit before bending.

Fig. 5 is a view similar to Fig. 4 on a slightly reduced scale showing a slightly modified arrangement of the strips in the encasing means.

Fig. 6 shows partially in end elevation and partially in cross section a modified form of encasing means.

Fig. 7 shows the modified form of Fig. 6 in side 20 elevation and illustrates both the initial and bent form of the encased unit.

Fig. 8 is a view similar to Fig. 6 showing another modified form of encasing means.

While the invention is susceptible of various 25 modifications and alternative constructions, I have shown in the drawings and will herein describe in detail the preferred embodiment, but it is to be understood that I do not thereby intend to limit the invention to the specific form or procedure disclosed, but intend to cover all modifications and alternative methods falling within the spirit and scope of the invention as expressed in the appended claims.

As previously mentioned, the present invention 35 finds particular application in the formation of the elongated strips of the peculiar form required in the installation of de-icer assemblies. Accordingly, the invention will be considered in this environment but it will be evident that the 40 novel method has wider application than in this specific instance.

Referring to the drawings, Fig. 1 illustrates a straight elongated strip of aluminum or aluminum alloy such as is used to fix the marginal edges of a de-icer "boot" to the straight sections of the leading edges of the wing or tail assemblies. This strip designated 10 is usually formed by an extruding process and in one form is about two inches wide. Its length is as required and its thickness varies from a relatively thick edge 45 about $\frac{1}{8}$ " or $\frac{3}{16}$ " thick to a thin feather edge 50 about $\frac{1}{16}$ " or $\frac{3}{32}$ " thick. It is slightly arcuate in transverse cross section so that its outer surface in assembly will complement the surface of the structure to which 55 it is secured.

The invention in this particular embodiment is employed to bend such strips into a form arcuate longitudinally substantially in the plane of the strip, the direction of bending being such that the feather edge 12 has the shorter radius.

Obviously bending thin metal strips in this fashion, whether the strips be flat or of arcuate cross section, is extremely difficult because the metal, particularly along the edge of shorter radius, will buckle or become transversely distorted so that the resulting strip would have an edge surface of generally serpentine form. This difficulty, of course, would increase to a considerable extent in the bending of a tapering sheet in which the inner edge is extremely thin.

According to the present invention, such strips may be conveniently bent to desired form with a minimum of rippling or buckling effect. Thus, a plurality of strips, having the straight form showing in Fig. 1, are stacked together in face-to-face abutment as shown at 13 in Fig. 4, and in this condition they are tightly confined so that they have approximately a unitary relation. To so confine the strips, encasing means is provided which in the present instance includes a pair of side plates 14 and a pair of end plates 15. The side plates 14 are complementary in form to the outside surfaces of the stack of strips, whereby these plates have substantially full surface engagement with the outer strips. The plates may be dimensioned so that all four sides of the stack are engaged and confined, but tight confinement of the edges on the outer or greater radius (the thicker edges as shown) is neither essential nor as desirable. The primary factor is tight, compressive lateral confinement throughout the areas where buckling ordinarily would occur.

The plates 14 and 15 are heavy sturdy members of steel or the like having sufficient strength substantially to prevent movement or displacement of metal laterally or transversely of the direction in which the unit is bent. The plates are rigidly secured together in any suitable manner, as by being welded together, as at 16. The welding is preferably done while the stacked strips and the encasing plates are under at least lateral compression.

The unitary assembly thus formed is then bent to the desired radius, the direction of bending in this particular form of strip being toward the feather edges thereof. This may be done in any well known manner as by rolling the unit in a roller or pressing it into the desired radius in a hydraulic press or a press brake.

When the encased unit has been formed to the desired radius the encasing plates 14 and 15 are removed and the stacked strips separated. In spite of the confining pressure on the strips while they are bent, it may be that small ripples, as indicated at 17 in Fig. 3, will have formed in the edge portion of the strip. These ripples, however, are relatively small, the extent of rippling being held to a minimum by the confining effect of the encasing means. I have found that the size of the ripples can be further reduced by first bending the encasing strips to a smaller radius than that desired in the completed form followed by a reverse bending to the desired radius. In other words, the strips are first bent too far as indicated by the dotted outline 18 (Fig. 3) followed by a reverse bending to the required radius as indicated by the full outline.

The ripples 17 are exaggerated and may be quite readily removed from the bent strip by any suitable operation. For example, the technique

used in reconditioning automobile fenders may be employed involving the hammering down of the high spots and filing or otherwise smoothing the strip into finished condition.

5 Strips for de-icer assemblies are used in pairs on the opposite margins. These pairs are substantially alike except that the transverse arcuate faces are reversed. The present invention may be used to form such pairs simultaneously. Thus, 10 as shown in Fig. 5, two stacks of strips are simultaneously encased in opposed relation as with the transverse arcuate faces of one stack opposing the arcuate faces of the other stack. The stacks could as well face in the opposite direction. The 15 two stacks are separated by a central partition 19 having opposite faces 20 complementary to the inner faces of each of the stacks. This partition accordingly is thin at the thick edges of the strips and thick at the feather edges. This partition together with the side plates 14 are arranged to complement and fully abut the exposed concave and convex surfaces of the strips. The 20 unitary structure thus formed is bent and the resulting strips are subsequently smoothed in the manner previously described. By this process opposed pairs of longitudinally bent strips may be conveniently and accurately formed.

In Figs. 6 and 7 a modified form of encasing means is shown which may be repeatedly used. The illustrated arrangement is one in which strips 30 in pairs are bent as in the form shown in Fig. 5, but it will be understood that a single set, stack or group of strips can be bent as well. Referring to Figs. 6 and 7, one surface of a base plate 21 of substantially heavy metal stock has a thin plate 22 integrally united along each longitudinal edge thereof as by welding, indicated at 23 (Fig. 7).

The side or lateral support comparable to that afforded by the side plates 14 of the encasing structure shown in Figs. 1 to 5 is provided by sets of thin flat plates 24 arranged to be stacked in flat face abutment on the plates 22. The outer edges 25 of the sets are fashioned to be in substantially perpendicular alignment to the base plate 21 while the inner edges 26 are shaped to complement the contours of the outer surfaces of a stack of strips to be bent. The assembled sets of plates 24 therefore have full surface engagement with the outer strips and provide the required lateral confinement. The plates 22, rigid with the base plate, provide inwardly facing shoulders which define fixed and laterally unyielding positions for the strips. A flat cover or top plate 27 completes the 35 encasing structure. Where, as shown, the strips are to be bent in opposed pairs, a center set of plates 28 is provided having edge surfaces 29 complementary to the surface portions of the strips to be engaged thereby.

Between their ends the base plate 21, the plates 22, the cover plate 27, and the plates 24 are preferably secured rigidly together on each side of the structure by a sturdy plate 30 welded or otherwise suitably secured to each of the individual parts. At the ends of the unit the parts may be less permanently but tightly connected as by U shaped members or clips 31 each arranged to straddle the top and sides of the unit with their ends extended through openings 34 in a base plate abutting cross bar 32. Nuts 33 on the extended ends secure the parts tightly together. Preferably the encasing unit is somewhat longer than the strips to be bent, as indicated at 34, to insure that the end portions of the strips will be bent to the same radius as the central portions.

The arrangement shown in Figs. 6 and 7 is to be preferred over the other form because great lateral resistance is provided by the series of thin, substantially unconnected plates, yet the unit has relatively high flexibility in the direction in which bending is to take place. The confining plates may be fashioned of mild or cold-rolled steel or made of spring steel so that after a bending operation they may be easily reshaped to their original flat form for reuse. During bending the plates of the assembly may shift relatively to some extent avoiding unnecessary stresses and distortion of the parts.

The modified form of encasing means shown in Fig. 8 is in effect substantially a combination of the forms of Figs. 4 or 5 and Fig. 6. Thus, referring to Fig. 8 the encasing means includes an end plate 35 (comparable to the end plate 15 at the thinner edges of the strips), side plates 36 (comparable to the side plates 14) and in the illustrated form a central partition 37 (comparable to the partition 19). The side plates and the end plate are welded together as in the form of Figs. 4 and 5. However, the opposite end plate at the thicker edges of the strips is a channel member 38 so dimensioned that its legs 39 fit snugly against the outer faces of the side plates 36. Centrally located lugs or reenforcing plates 40 (comparable to the lugs or plates 30 of the form of Figs. 6 and 7) are preferably secured, as by welding, to the legs 39 of the channel member and the end plate 35. At each end the parts of the encasing unit Fig. 8 may be secured together by the same clip means described in connection with the unit of Figs. 6 and 7. Since these parts are unchanged they are indicated by the same reference numerals.

The encasing unit of Fig. 8 is advantageous in that it may be quickly and easily assembled and disassembled. Moreover it affords the necessary transverse rigidity opposing the tendency of the thinner edges of the strips to buckle while being somewhat less confining to the thicker edges. This factor is important in that it permits the thicker edges some movement other than lateral during the bending operation.

It will be evident from the foregoing that a novel method of bending an elongated thin and relatively wide strip edgewise into a form which is arcuate longitudinally substantially in the plane thereof has been provided. The process is simple and may be rapidly carried out. While a single strip may be bent according to the process if desired, efficient production practices make the simultaneous bending of a plurality of strips more desirable. It will, of course, be understood that the present invention has utility in the bending of strips that are not of tapering arcuate cross section.

I claim as my invention:

1. The method of bending thin elongated metal strips in the plane thereof while avoiding substantial buckling along the strip which includes the steps of tightly confining a plurality of such strips in stacked face-to-face abutment and supporting the entire face of each strip within a bendable encasing means which is rigid in a direction transversely of the stacked strips, bending the encasing means with the stacked strips therein in a direction which bends the strips edgewise, thereby bending the strips to a smaller radius than the radius desired, reversely bending said encasing means and strips to the desired radius, removing the encasing means, and smoothing such irregularities as may have resulted during bending.

2. The method of bending thin elongated metal strips of arcuate cross section in the plane thereof while avoiding substantial buckling along the strip which includes the steps of tightly confining a plurality of such strips in stacked face-to-face abutment and supporting the entire outer side faces of each strip within a bendable encasing means which is rigid in a direction transversely of the stacked strips having full face contact with the outer side faces of the stacked strips, bending the encasing means with the stacked strips therein in a direction which bends the strips edgewise, and thereby bending the strips to a smaller radius than the radius desired, reversely bending said encasing means and strips to the desired radius, removing the encasing means, and finishing the strips.

3. The method of bending thin elongated metal strips having a cross sectional form which is arcuate and tapers in thickness, the direction of bending being substantially in the plane thereof which includes the steps of confining under compression a plurality of such strips in face-to-face abutment and supporting the entire face of each strip within a bendable encasing means which is rigid in a direction transversely of the stacked strips, bending the encasing means with the stacked strips therein in a direction which bends the strips edgewise, and thereby bending the strips to a smaller radius than the radius desired, and reversely bending said encasing means and strips to the desired radius.

4. The method of bending edgewise thin elongated metal strips of arcuate cross section which includes the steps of arranging a plurality of such strips in stacked face-to-face abutment, confining and supporting the entire faces of a pair of such stacks within a rigid encasing means which is rigid in a direction transversely of the strips, with the arcuate faces of the stacks disposed oppositely, bending the encasing means with the stacked strips therein in a direction which bends the strips edgewise, and thereby bending the strips to a smaller radius than the radius desired, and reversely bending said encasing means and strips to the desired radius.

5. The method of bending edgewise thin elongated metal strips which have a cross sectional form arcuate and of tapering thickness which includes the steps of confining such strips in opposed relation within a rigid but bendable encasing means, maintaining by said confining means full surface abutment with at least one of the edges and with the exposed convex and concave surfaces of said strips, bending the encasing means with the strips therein in a direction which bends the strips edgewise, thereby bending the strips to a smaller radius than the radius desired, and reversely bending said encasing means and strips to the desired radius.

6. The method of forming thin and wide metal strips of arcuate cross section into pairs of complementary strips having a form arcuate lengthwise substantially in the plane thereof which includes applying a bending force to a pair of oppositely facing strips to bend them edgewise while confining the edges and side faces of the strips on the inner radius tightly against buckling, and thereby bending the strips to a radius greater than desired, and while the strips remain so confined reversely bending them to a desired radius.

7. The method of bending thin and wide metal strips to curve such strips lengthwise substantially in the planes thereof without substantial buckling of the side edges toward which such

strips are bent, which comprises, compacting a bundle of such strips in face-to-face stacked relation with reenforcing members overlying the opposite faces of the stack and contacting such faces throughout the entire areas of the same which are to be bent, and applying bending forces to said reenforcing members to bend the same and the confined bundle of strips edgewise while retaining the bundle tightly confined by the reenforcing members in the course of the simultaneous bending of the reenforcing members and bundle of strips.

8. The method of bending thin and wide metal strips to curve such strips lengthwise substantially in the planes thereof without substantial buckling of the side edges toward which such strips are bent, which comprises, stacking a bundle of such strips in face-to-face relation, compacting the bundle by pressing a pair of metal reenforcing plates against the opposite faces of the stack, which plates are of heavy stock as compared to the strips and dimensioned to con-

tact the faces of the stack throughout their entire area for the length of the same which is to be bent, permanently seaming a pair of top and bottom plates to the edges of the first-mentioned reenforcing plates, bending the stack of strips and encasing plates in a direction edgewise of the stack, and breaking the seams and removing the reenforcing plates only after the bending is completed.

9. The method of bending edgewise thin elongated metal strips of arcuate cross-section which includes the steps of arranging a plurality of such strips in stacked face-to-face abutment, confining and supporting the entire faces of a pair of such stacks within a bendable encasing means which is rigid in a direction transversely of the strips and with the arcuate faces of the stacks disposed oppositely, and bending the encasing means with the stacked strips therein in a direction which bends the strips edgewise.

WILLIAM SCHUKRAFT.
